UNITED STATES PATENT OFFICE.

JOSEPH B. MATTHEWS, OF BALTIMORE, MD., ASSIGNOR OF ONE-HALF TO
BETTS MACHINE COMPANY, OF WILMINGTON, DEL.

FEED-MOTION FOR METAL-PLANING MACHINES.

SPECIFICATION forming part of Letters Patent No. 239,969, dated April 12, 1881.

Application filed November 24, 1880. (Model.)

To all whom it may concern:

Be it known that I, JOSEPH B. MATTHEWS, of Baltimore city, State of Maryland, have invented certain new and useful Improvements 5 in Feed-Motions for Metal-Planing Machines; and I hereby declare the same to be fully, clearly, and exactly described as follows, reference being had to the accompanying drawings, in which—

10 Figure 1 is an elevation of a device embodying my present invention, the covering gear-wheel being removed. Fig. 2 is a similar view of the latter. Fig. 3 is a side elevation of the device complete. Fig. 4 is an enlarged view 15 of the reversing-pawl; and Fig. 5 is a sectional view of the tip of the latter.

My invention relates, in general, to machines for planing metal, and, in particular, to that portion of the machine constituting the 20 devices for feeding the cutter vertically and laterally, and for lifting its point clear of the work pending the return-stroke of the latter.

My invention is applicable to planing-machines of the usual or ordinary construction, in 25 view of which fact I have considered it unnecessary to illustrate in the accompanying drawings, and shall not particularly describe, the construction and arrangement of those portions of the planer not germane to my invention and constituting no part of the same. Suffice it that they embody a bed-plate arranged to carry the work and to reciprocate beneath the cutter, which latter is arranged in guides susceptible of lateral and vertical 30 motions with reference to the bed-plate.

The cutter is fed by the usual screw, ratchet, segment-rack, and pitman-rod, and the bed-plate is actuated by a gear-wheel mounted on a transverse shaft beneath the machine. The 35 mechanism for reversing the motion of the bed-plate or table and shifting the belt may be of any desired and suitable construction.

Proceeding to describe those portions of the machine germane to my present invention and 40 illustrated in the accompanying drawings, but which portions are of the usual or well-known constructions, N is a disk mounted on the end of the shaft C, and having a dovetail groove on its face, in which is mounted a screw-rod 45 actuated by a crank, n. A block pivoted on

the end of the pitman-rod is mounted upon this screw-rod and slides in the dovetail groove.

The throw of the rod, as the disk is turned, is regulated by the crank n, being, of course, measured by the radial distance of the block 55 from the center of the disk. O is a crank having a terminal groove for the cord, which lifts the cutter-point pending the return-stroke of the bed-plate.

Before describing the parts of the machine 60 embodying my invention the object of the latter may be concisely stated, as follows: It is designed to furnish a mechanism for positively driving the shaft C, which communicates motion to the feed device, but which mechanism 65 shall be so constructed as to automatically yield before the end of the stroke of the disk is reached, or upon the interposition at any point in the feed machinery of an obstacle. Upon the happening of this contingency the 70 pawl constituting the positive feed-mover automatically reverses without strain or injury to the machine or to the obstacle—a point of the highest importance in view of the fact that the latter is liable to be the hand of the operator, which is sometimes caught between the 75 segment-rack and its pinion.

A is a casing having a sleeve, a', in which the shaft C turns, which casing is secured to the main frame of the machine, near the transverse shaft, by bolts passing through holes a. On the shaft C turns freely the wheel H, which is hollow, as shown in Fig. 2, and is provided with a central sleeve, c', and with external teeth, M, that mesh with those of a gear-wheel 80 on the transverse shaft, beneath the bed-plate, and with an internal series of shallow teeth, J, 85 which latter constitute the ratchet.

D is a plate which, together with the wheel H, constitutes a box, as it were, containing the 90 pawl mechanism. The parts D and H are secured together by screws passing through the holes d l.

A bar or arm, e, is secured to the shaft C, and has arms e e, between which slides the 95 block E, that is mounted on the end of a rod, g. This latter passes through the shaft C and is normally thrust outward by means of a spring, G. A lug or set-screw, F, passes through one of the arms e and enters a slot, f, 100

in the block E, limiting the motion of the latter. One inner edge of the block E is beveled, as shown at *o*, (see Fig. 4,) and against this beveled portion a pin, *m*, is caused to press by 5 means of a spring, *L*.

In the end of the block E is pivoted the reversible pawl *h*, which is perforated near its tip, and in the perforation are a pair of pins, *i i'*, that are normally thrust outward by means 10 of a spring, *i'*. The pawl is susceptible of a motion, substantially in the area about its pivot, somewhat less than through a half-circle, the motion of the pawl about its pivot being, in a word, less than sufficient to bring the path *y* 15 *y'* described by the pins *i* into coincidence with the path *x x'* described by the pivot as the arm *c* turns, and less than sufficient to bring the axis *w w'* of the pawl to a position at right angles to the axis of the rod *g*. The 20 angle between the line *w w'* and the axis of the rod *g* should be about seventy degrees. On the casing A are a pair of stops, *b*, against which the arm *c* abuts at the end of its stroke, and which permit the arm to turn through 25 about a half-circle.

Such is the construction of the device.

In operation the wheel *H* is driven by the gear-wheel on the main shaft of the machine, the motion of which is reversed in the usual 30 way. As this reversal of motion occurs the pawl *h* engages with the ratchet *J*, and the shaft *C* is caused to turn, carrying with it the disk *N* and effecting the throw of the pitman-rod, as will be readily understood. When the 35 arm *c* brings up against the stop *b* the further motion of the wheel *H* simply represses the pawl-rod *g*, and tilts the pawl over in position for engagement with the ratchet on the return-stroke.

40 The object of the pins *i* is twofold: being caused by means of the spring *i'* to press outward against the sides of the wheel *H* and the plate *D*, the slight friction thereby caused results in a traction upon the pawl-tip in a line 45 tangent to the arc *y y'*, whereby the pawl is held out of contact with the ratchet, and the noise and clicking which would otherwise result are avoided.

As the motion of the wheel *H* is reversed 50 the frictional contact of the pins with the wheel and plate *D*, acting in connection with the weight of the pawl, quickly swings the pawl into engagement with the ratchet. The resistance to the repression of the rod *g* incident 55 upon the angularity of the thrust with the axis of the rod and upon the resistance of the spring *G*, is supplemented in an important manner by the pin *m* and incline *o*.

These elements serve to resist the inception 60 of the repression of the rod and hold the pawl with practical rigidity, while still offering no

material resistance after the motion is once started. The immense advantages of the device over the old frictional feed-motions are at once evident. The latter are uncertain in their 65 operation, are liable, upon the entrance of a little oil, to refuse to work at all, require constant adjustment, and are, in effect, no positive motions at all.

The present device is simple, not liable to 70 get out of order, is readily applicable to planers already in use, and, while affording a positive feed, is yet of such construction that should the hand of the operator be caught, as so frequently occurs in the feed machinery, the parts 75 yield by the tilting of the pawl, and no injury results to either machine or operator.

What I claim as new, and desire to secure by Letters Patent, is—

1. The combination, in a feed-motion for 80 planing-machines, with the driving-gear, of a wheel, ratchet, and pawl, the said pawl being adapted to automatically tilt, so as to engage with the ratchet on either side upon the reversal of the motion of the wheel, as set forth. 85

2. The combination, in a feed-motion for planing-machines, with the wheel having a ratchet, of the reversible pawl, provided with mechanism whereby it is held out of engagement with the ratchet until the motion of the 90 wheel is reversed, as set forth.

3. In a feed-motion for planing-machines, the combination, with the driving-wheel and ratchet, of the reversible pawl having friction-pins *i*, as set forth. 95

4. In a feed-motion for planing-machines, the combination, with the driving-wheel and ratchet, of a reversible pawl pivoted upon a retractile rod and adapted to tilt, as set forth.

5. In combination with the driven wheel and ratchet, a reversible pawl pivoted upon a block having a bevel, *o*, and spring, *m*, whereby the inception of the stroke necessary to reverse the pawl is resisted, as set forth. 100

6. In combination with the driven wheel and ratchet, the pawl pivoted upon the block *E*, having bevel *o*, pin *m*, slot *f*, and lug *F*, as set forth. 105

7. In combination with the driven wheel having ratchet, the reversible pawl *h*, rod *g*, and spring *G*, as set forth. 110

8. The casing *A*, having stops *b*, and sleeve *a'*, in combination with the shaft *C*, arm *c*, reversible pawl, and disk *N*, as set forth. 115

9. In combination with the casing, having stops *b* and sleeve *a'*, the shaft *C*, arm *c*, rod *g*, spring *G*, and reversible pawl *h*, as set forth. 120
